H. C. PRIEBE,
CAR UNDERFRAMING,
APPLICATION FILED MAY 2, 1918.

1,302,087.

Patented Apr. 29, 1919.

UNITED STATES PATENT OFFICE.

HERMAN C. PRIEBE, OF BLUE ISLAND, ILLINOIS.

CAR-UNDERFRAMING.

1,302,087.

Specification of Letters Patent. Patented Apr. 29, 1919.

Application filed May 2, 1918. Serial No. 232,028.

To all whom it may concern:

Be it known that I, HERMAN C. PRIEBE, a citizen of the United States of America, residing at Blue Island, in the county of 5 Cook and State of Illinois, have invented certain new and useful Improvements in Car-Underframing, of which the following is a specification.

This invention relates to railway cars and 10 more particularly to that part referred to as the underframing for supporting the draft gear.

One of the objects of the present invention is to provide an improved underframing construction of such simple and compact arrangement as to be more durable and reliable than the constructions in use prior to this invention. Another object is to so position, arrange and connect the various elements and parts forming the underframe construction as to prevent relative longitudinal and lateral movements thereof under the shocks and strains to which the car is subjected particularly in the coupling and 25 uncoupling operations. A further object is to provide a structure of the above general character which may be easily and inexpensively manufactured and assembled and permit the installation of draft gear of any desired type with a minimum amount of trouble.

Other objects will be in part obvious from the annexed drawings and in part indicated in connection therewith by the following 35 analysis of this invention.

This invention accordingly consists in the features of construction, combination of parts and in the unique relations of the members and in the relative proportioning 40 and disposition thereof; all as more completely outlined herein.

To enable others skilled in the art so fully to comprehend the underlying features thereof that they may embody the same by 45 the numerous modifications in structure and relation contemplated by this invention, drawings depicting a preferred form have been annexed as a part of this disclosure, and in such drawings, like characters of reference denote corresponding parts throughout all the views, of which:

Figure 1 is a plan and partial sectional view of such parts of the underframing as are necessary to fully understand the present 55 invention;

Fig. 2 is a side elevation of the parts

shown in Fig. 1 with the end sill in section;

Fig. 3 is a sectional view taken substantially along the line 3—3 of Fig. 2; and

Fig. 4 is a sectional view taken on the 60 line 4—4 looking in the direction of the arrows.

Referring now to the drawings in detail, 5 denotes a pair of separated longitudinally disposed members, preferably wooden 65 beams, constituting the center sills of the car. These beams are embraced along the bottom and underside by angle irons 6 of L-shaped cross sections connected at their forward parts, that is, the left hand side in 70 the drawings, with channel beams 7 forming the draft sills and at their rear parts or right hand portion, as shown in Figs. 1 and 2, with sub-center sills 8. Between the draft sills and sub-center sills 8 is a space 75 10 within which is adapted to be mounted the transverse body bolster of the car. As this forms no part of the present invention, it is believed to be unnecessary to show the same in detail having been described and 80 claimed in combination in my prior Patent #1,253,187, January 8, 1918. Strengthening irons 11 are secured to the angle iron 6 above this point.

The forward or left hand ends of the 85 angle irons 6 are provided with relatively small vertically disposed abutments 12, as shown in Fig. 4, which are riveted at 13 to the angle irons 6 and are adapted to abut an end sill 14 extending across the end of 90 the car above the draft sills 7. This construction increases the relative area of the main center sill at its point of engagement with the end sill to better take up the shocks and strains to which the underframing is 95 subjected.

The end sill 14 must be held firmly in position against both relative lateral and longitudinal movement with respect to the other parts. It is upon this sill that the 100 greatest strains are exerted because of the momentum of the weight supported by the center sills of the car in starting and stopping. Suitable bolts 15 are therefore provided which pass downwardly through 105 the end sill and registering holes in one or both of the flanges of the draft sills 7. These bolts may be of any desired type and may be provided with lock nuts 18 at either the top or bottom as desired for holding the parts in assembled position.

The inner or adjacent surfaces of the

draft sills 7 are provided with malleable iron castings 20 provided with holes 21 registering with corresponding holes in the draft sill members through which transverse bars are adapted to be passed for supporting the draft gear, as shown in my above referred to patent. For the sake of clearness, the draft rigging has been omitted as it is of well known construction and 10 forms no special part of the present invention.

It will thus be seen that the invention herein illustrated and described embodies a simple and practical construction in which 15 the parts are so positioned and arranged as to allow maximum flexibility yet at the same time provide a most durable, reliable, and efficient construction fully capable of resisting all of the strains and shocks to 20 which the parts may be submitted.

Without further analysis, the foregoing will so fully reveal the gist of this invention that others can by applying current knowledge readily adapt it for various applications without omitting certain features that, 25 from the standpoint of the prior art, fairly constitute essential characteristics of the generic or specific aspects of this invention, and therefore such adaptations should and 30 are intended to be comprehended within the meaning and range of equivalency of the following claims.

I claim:

1. In an underframe construction, in combination, a main center sill composed of 35 two separated beams, a draft sill associated therewith comprising two flanged channel irons adapted to be supported by the center sill members along their upper edges, L-shaped angle irons on the adjacent sides of 40 the center sill beams and securing the draft sill members to the center sill members, a

transverse end sill above the draft sill members and at one end of the center sill members, angle irons secured to each center sill 45 member abutting the end sill, vertically disposed tie bolts passing through the end sill and flanges of the draft sill members adapted to prevent relative longitudinal and lateral movement of the end sill with respect to the draft sill members, and malleable iron castings secured to the vertical sides of said draft sill members for supporting the draft rigging.

2. In an underframing construction, in combination, a main center sill composed of two separated beams, L-shaped angle irons covering the adjacent and bottom faces of said beams, a draft sill comprising a pair of flanged channel irons supported by 60 the center sill members along their upper edges, metallic members securing the draft sill to the center sill, and a transverse end sill above the draft sill members and at the end of the center sill.

3. In an underframing construction, in combination, a main center sill, composed of two separated beams, a draft sill comprising two flanged channel irons supported by the center sill along their upper edges, 70 an end sill above the draft sill and at the end of the center sill, tie members passing through the end sill and draft sill, and malleable iron castings having perforations secured to the inner vertical sides of said 75 draft sill members through which draft bars are adapted to be passed.

In testimony whereof I affix my signature in the presence of two witnesses.

HERMAN C. PRIEBE.
